UNITED STATES PATENT OFFICE.

SAMUEL W. DORSEY, OF DES MOINES, IOWA.

TENT.

1,045,132.

Specification of Letters Patent.

Patented Nov. 26, 1912.

Application filed July 3, 1911. Serial No. 636,723.

To all whom it may concern:

Be it known that I, SAMUEL W. DORSEY, a citizen of the United States, residing in Des Moines, in the county of Polk and State 5 of Iowa, have invented a certain new and useful Improvement in Tents, of which the following is a specification.

The object of my invention is to provide a tent having windows formed in the sides 10 thereof, by cutting flaps integral with the tent walls.

A further object is to provide such a tent with windows, and flaps formed between the seams of the tent sides, and provided with 15 means for securing flaps in their closed positions, which means are secured to the flaps, and to the tent wall on the seam, in such a way, that the formation of the windows does not in any way weaken the tent walls.

20 A further object is to provide detachable, flexible screens for the windows in said tent, with means whereby said screens may be readily secured in position.

My invention consists in certain details in 25 the construction, arrangement and combination of the various parts of the device, whereby the objects contemplated are attained, as hereinafter more fully set forth, pointed out in my claim and illustrated in 30 the accompanying drawings, in which—

Figure 1 shows a perspective view of a tent embodying my invention, and equipped with my improved tent screens. Fig. 2 shows a detail view of the means for fastening the flaps in their closed position. Fig. 3 shows a detail, sectional view of the means for reinforcing the tent fabric around the 35 window openings. Fig. 4, shows a detail, perspective view, enlarged of one of my improved tent screens, and Fig. 5 shows a detail, sectional view of a portion of the frame 40 of the screen, shown in Fig. 4.

In the accompanying drawings, I have used the reference numeral 10, to indicate 45 a wall tent. My improved screens and flaps may be used with any tent, but are preferably used with a wall, or an A tent, composed of strips of material 11 connected by seams 12. In the sides of the tent, I cut an 50 opening of any desired shape, thereby forming a flap 13, the upper end of which is integrally connected with the tent wall. The window opening just described, is preferably formed between two seams, and extends 55 approximately from one seam to the next adjacent seam. As many window openings

may be cut as desired. The flap 13, by its own weight, hangs normally in position to close the window opening. The flap 13 may be rolled up, and I provide two cords or 60 strings 14 adjacent to each end of the upper portion of the flap 13, for tying said flap when it is rolled up. At each lower corner of the flap 13, is secured a leather loop 15 in which is secured an ordinary snap catch 65 16. A leather loop 17 is secured to a seam and a ring 18 is mounted therein in proper position to be engaged by the snaps 16, secured to the flaps on each side of the seam. It will thus be seen that the seam 12 which 70 receives the strain when the tent is pitched, is not weakened by cutting the flap 13 in the tent wall, and that the flaps are cut at such points in the wall, and the fastening devices thereon, are so arranged, that the 75 flaps are fastened down by securing them to the seam, thus retaining all the strength of the tent wall. Around the edge of the opening formed when the flap 13 is cut in the tent wall, I bind a reinforcing folded strip 80 of canvas 19, as shown in Fig. 5 with the edges of the tent wall adjacent to the opening received within the fold of the strip 19. The folded strip 19 around the edge of the window opening, thus forms a window 85 frame.

My improved screen comprises a frame 20 of flexible material, preferably heavy canvas, which is of proper shape to cover the window openings in the sides of the 90 tent. In the frame 20 is secured a suitable fine mesh netting 21. My screen is preferably made by using a folded strip of canvas for the frame 20, and securing the netting 21 to the frame 20 within the fold 95 thereby, as clearly shown in Fig. 3.

My improved tent screens may be secured to the windows in any suitable way. For obvious reasons, they are preferably fastened to the tent wall. In the drawings, I 100 have shown ordinary clasp buttons 22 secured to the folded strip 19 around the window opening, which buttons are received in the coacting members 23, in the frame 20 of the flexible screen.

It will be seen that many changes may be made in details of construction of the parts of my improvement in tents without departing from its important features. The form and material of the loops 15 and 17, and the 110 fastening devices thereon, are not material. It is however important that the fastening

devices should be secured at proper places, so that the flaps may be secured to the seams of the tent. The material and construction of the flexible screens may be varied in many ways, so long as the screens may be readily folded, and may be easily and quickly attached to the frame of the window opening.

In the practical construction and use of my improvement in tents, the flaps 13 are cut from the tent wall, leaving them integral with said wall at their upper ends. The cords 14 which may be of any suitable material, as leather, metal or cloth, are then secured near the upper ends of the flap 13. The folded strip 19 is then sewed or otherwise secured around the window opening, thus formed, making a frame therefor. The screens may be made in many ways, but as shown in the drawings are made by folding a strip of canvas double and making a rectangular or other shaped frame 20, and securing within the fold of the frame, a suitable screen or netting 21. Any suitable fastening devices may be used for securing the screen to the window. As shown in the drawings, clasp buttons 22 may be secured to the folded strip 19 on the inner side of the tent wall, and coacting members 23 designed to receive the buttons 22 secured to the frame 20. The screen is buttoned over the window, as shown in Fig. 4. The flaps 13 may be fastened down outside the screen, as shown in Fig. 2, or may be rolled up, as shown in Fig. 1. A portion of the screen may be unbuttoned and the flap 13 may be manipulated from the inside of the tent.

An important advantage of the form and location of my flap 13, is found in the fact that the window opening is cut between the seams of the tent wall, which receive the strain when the tent is pitched, and the tent wall is not materially weakened. The flaps are fastened at their lower ends on the seam, thus avoiding any tearing of the tent fab-

ric or weakening the tent wall by securing fastening devices thereto in the weaker parts thereof. Another special advantage is found in the construction of the flexible screen, which may be folded and packed into a small space for storage or transportation, which is quickly and easily attached to, or detached from the tent window, and is readily repaired. The flexible frame 20 furnishes a strong support for the netting 21 and at the same time may be folded and partially detached from the window to permit the manipulation of the flap 13 on the inside, during rain storms or cold weather.

I claim as my invention:

In a device of the class described, a tent wall formed of a number of vertically arranged strips of material connected by seams, a number of the strips being formed with an opening, a reinforcing strip surrounding said opening, fastening members on the interior of such reinforcing strip, screens of flexible material, each provided with a flexible reinforcing frame and with coacting fastening members at its top, sides and bottom, for detachably securing the screens to the inner surfaces of the strips of material, whereby the operator may, by detaching the upper fastening members, obtain access to the outside flap and the fastening members above the opening on the outside, and whereby the screen, when in position, will support the wall against movement tending to stretch the sides or the top and bottom of the openings apart, the fastening members for securing the flap on the outside in its closed position, being designed to reinforce and support the wall against upward and downward stretching.

Des Moines, Iowa, June 21, 1911.

SAMUEL W. DORSEY.
